Attorneys

UNITED STATES PATENT OFFICE.

ROBERT C. RUSSELL, OF PITTSBURGH, PENNSYLVANIA.

CARD INDEX.

Application filed October 2, 1923. Serial No. 666,099.

To all whom it may concern:

Be it known that I, ROBERT C. RUSSELL, a citizen of the United States, and resident of Pittsburgh, in the county of Allegheny and State of Pennsylvania, have invented certain new and useful Improvements in Card Indexes; and I do hereby declare the following to be a full, clear, and exact description of the invention, such as will enable others skilled in the art to which it appertains to make and use the same.

This invention relates to improvements in card indexes and more particularly to that of the "visible" type,—one object of the invention being to provide simple and efficient means for connecting the index card with its support and for effectually applying a transparent shield to the card to cover a face thereof.

With this and other objects in view, the invention consists in certain novel features as hereinafter set forth and pointed out in the claims.

In the accompanying drawings;

Figure 1 is a face view illustrating a card index embodying my improvements;

Figure 2 is a longitudinal sectional view of the card holder;

Figure 3 is a view in section on the line 3—3 of Figure 1;

Figure 4 is a perspective view showing an index card with shield applied and the card-support separated;

Figure 5 is a perspective view of the shield;

Figure 6 is a front elevation of a card with applied shield and a card-support separated, and showing a modified construction, and

Figure 7 is a view illustrating the parts shown in Figure 6 assembled.

In Figures 1 and 2 of the drawing, a holder 1 is shown as having side flanges 2 bent to form guide-ways for tongues 3 projecting from card-supports 4. One end of the metal sheet forming the holder is bent to overlie the lower portion of the holder and provides a platform 5 upon which the bottom card of the series may rest and permit the overlying cards to be disposed flatly.

The lower portions of the side flanges 2 of the holder may be bent downwardly close against the platform 5 as at 6 and thus close the lower ends of the guideways and the upper end of the platform 5 may constitute

an abutment for the support of the bottom card.

In Figure 1 of the drawing, a plurality of index cards 9 and their supports are shown in the holder 1, each card being provided with a shield 10.

Each support 4 is provided with a member 11 hinged thereto and in effect forming part thereof. In one embodiment of the device, the member 11 is hinged to the body 65 of the support by means of a fabric strip 12 cemented to the respective parts and provided with a slot 13, as most clearly shown in Figure 4. A tongue 14 projects upwardly from the central portion of support and, when the cards with their supports are in the holder as illustrated in Figure 1, the tongue 14 of one support will project through the slot 13 in the hinge connection between the superimposed card and its support, and 70 thus the several cards with their supports will be united by interlocking or intermeshing connnections.

The hinged member 11 of each card-support is provided near its ends with eyelets 80 (or solid pins or rivets may be employed), the heads 16 at the front ends of which are spaced slightly from the front face of the holder member 11. Each index card 9 is provided at its respective ends with open 85 slots or notches 17 for the accommodation of the eyelets and so that portions of the card may engage behind the heads of said eyelets, thus removably connecting the index card with the hinged member of its holder. 90

The shield 10 for the card may be made of transparent material, such as celluloid and is made sufficient in size to cover practically the entire front face of the card including the slotted portions thereof. The 95 shield is provided at its lower edge with an upturned flange 18 which is resilient and normally tends to clamp the lower portion of the card in the pocket formed between said flange and the body of the shield. The 100 shield is provided at its upper edge with a downwardly turned resilient flange 19 which serves to clamp the upper portion of the shield to the card.

It will be apparent from the construction and arrangement of parts above described, that the shield which covers the front face of the card is removably connected with the card so that the latter may be reversed if desired, and that the card, carrying the 110

shield, is removably connected with the holder. The cards of the index may be changed as desired while the supports are permitted to remain in the holder, and when 5 in use, both faces of the lower portions of the cards will be protected by the shield against injury or soiling.

Instead of providing the hinged members of the card supports with headed eyelets or 10 rivets to receive the slotted portions of the cards, as above described, the cards may be provided at their upper corner portions with tongues 20 to pass through slots 21 in hinged member 11, as illustrated in Figures 15 6 and 7.

Having fully described my invention what I claim as new and desire to secure by Letters-Patent, is:—

1. In a card index, the combination with 20 a support including a hinged member, of an index card, and means whereby the index card is removably connected with the hinged member of the support, and a transparent shield applied to the card and covering the means whereby the card is connected with the hinged member.

2. In a card index, the combination with 30 a support including a hinged member, of headed devices carried by said hinged member, an index card having slots to receive said headed devices and effect removable connection of the card with the hinged support member, and a transparent shield ap-

plied to the card and covering a face of the same and also said headed devices. 35

3. In a card index, the combination with a support including a hinged member, of an index card removably attached to said hinged member, and a transparent shield carried by and covering one face of the 40 card, said shield provided at its upper and lower edges with resilient flanges engaging the other face of the card near the upper and lower edges of the latter.

4. In a card index, the combination of a 45 support including a hinged member, headed devices carried by said hinged member near the ends thereof, an index card having notched portions near its upper corners to removably engage said headed devices, and 50 a transparent shield having upper and lower resilient flanges to engage the index card.

5. In a card index, the combination with a support including a hinged member, and 55 an index card attached to said hinged member, of a transparent shield covering a face of the card and removably connected therewith adjacent its upper and lower edges.

In testimony whereof, I have signed this 60 specification in the presence of two subscribing witnesses.

ROBERT C. RUSSELL.
